(57) **CLAIM**

The ornamental design for an external cam lock, as shown and described.

DESCRIPTION

FIG. 1 is a perspective view of an external cam lock showing my new design;

FIG. 2 is a top view of thereof;

FIG. 3 is a rear view of thereof;

FIG. 4 is a front view of thereof;

FIG. 5 is a side view of thereof;

FIG. 6 is a side view of thereof; and,

FIG. 7 is a bottom view thereof.

The broken lines are for illustrative purpose only and form no part of the claimed design.
